UNITED STATES PATENT OFFICE.

JOSEPH BECKER, OF WASHINGTON, DISTRICT OF COLUMBIA, ASSIGNOR TO EASTMAN KODAK COMPANY, OF ROCHESTER, NEW YORK, A CORPORATION OF NEW YORK.

COPYING OR ENLARGING CAMERA.

1,343,889.

Specification of Letters Patent. Patented June 15, 1920.

Original application filed December 11, 1915, Serial No. 66,371. Divided and this application filed April 21, 1919. Serial No. 291,472.

To all whom it may concern:

Be it known that I, JOSEPH BECKER, a citizen of the United States, residing at Washington, in the District of Columbia, have invented a certain new and useful Improvement in Copying or Enlarging Cameras, of which the following is a specification.

My present application for patent, identified for convenience of reference in my related applications or patents as Case Bf, is Division Two of my prior application, Case Ae, now Patent No. 1,301,897, granted Apr. 29, 1919.

The present application and my herein specifically referred to applications or patents, may be listed in their letter name, or filing date order, as follows: Case A, filed August 11, 1900, now Patent No. 1,178,474, issued April 4, 1916; Case K, now Patent No. 1,103,342, issued July 14, 1914; Case O, now Patent No. 1,103,343, issued July 14, 1914; Case T, now Patent No. 1,142,295, issued June 8, 1915; Case U, now Patent No. 1,190,214, issued July 4, 1916; Case X, Serial No. 727,548, filed October 24, 1912, now merged in Case Bd; Case Y, filed November 20, 1912, now merged in my lately patented Case Au, whose Figures 1 to 7 are copied from the Case Y figures; my above referred to parent application, Case Ae, Serial No. 66,371, filed December 11, 1915; Case Ai, or Division Two of A, Serial No. 88,619, filed April 3, 1916, now merged in Case Bc; Case At, Serial No. 143,085, filed January 18, 1917; Case Au or continuation of Y, now Patent No. 1,280,638, issued October 8, 1918; Case Bc continuing Ai or Division Two of A, Serial No. 255,491, filed September 24, 1918; Case Bd, merging Case X, Serial No. 258,467, filed October 16, 1918; Case Be, or Division One of my Case Ae, Serial No. 290,486 filed April 16, 1919; and my present Case Bf, or Division Two of Ae, Serial No. 291,472, filed April 21, 1919.

My present invention relates to copying or enlarging cameras, and it consists in the separately patentable obtuse angle radial cam type of wholly mechanical focuser which is disclosed in Figs. 1 to 10 of my said Case Ae, and which may always be regu-

lated and adjusted to operate in strict accordance with Newton's formula, to wit:

$$PF.F'P' = f^2 \quad (1) \quad 55$$

or with the better known mathematical equivalent lens formula:

$$\frac{1}{PN} + \frac{1}{N'P'} = \frac{1}{f} \quad (2) \quad 60$$

In the accompanying drawings:

Fig. 1, is a vertical axial section of a copying or enlarging camera fully adjusted and regulated for coöperation with a wholly mechanical radial cam focuser whose basic angle delta (Δ) is 108° or $1.20 Q$; that is to say, it is twenty per cent. larger than the right angle or quadrant.

Fig. 2 shows how the dimension m of the left carriage Fig. 1, is automatically made equal to the unknown dimension x of the lens frame, by focusing on right hand infinity.

Fig. 3 shows how the dimension m' of the right hand carriage of Fig. 1, is automatically made equal to the unknown dimension x' of the lens frame, by focusing on left hand infinity.

Fig. 4 is a diagram of all the fundamental linear and angular elements in Fig. 1.

The camera of Figs. 1 to 4 has a basic angle delta (Δ) of 108° degrees of six-fifths of a right angle. That is to say, delta (Δ) here equals $1.20 Q$, as indicated in Fig. 1. 85

The bed 510 of this form has a slideway 511 for two carriages 512 and 512'; and in the carriage 512 is formed a longitudinal slideway 505 for a slide block 506, which directly supports the object frame O^s and which has a set-screw 507 for fixing the object frame O^s in any desired longitudinal adjustment on the said carriage 512. The image frame I^s is similarly fixed, in any desired longitudinal adjustment on carriage 512', by means of set-screw 507' threaded in the slide block 506' of slideway 505'. The lens frame L^s carrying the lens 509 is rigidly fixed to bed 510 by screws 503, and it is recessed below to provide the free sliding room 100 that is needed to permit of bringing carriage 512' into its zero position, the posi-

tion seen in Fig. 3 and fully described later on.

To the under side of carriage 512 is fastened by screws, such as 513, 513, a bracket 514 having an inclined groove 515 to provide adjustment for clamping the object frame pintle 519 where desired on said bracket 514. To the under side of carriage 512' is similarly fastened by screws 513', 513' a bracket 514' having an oppositely inclined groove 515' to provide adjustment for clamping the image frame pintle 519' where desired on the said bracket 514'. The axes of said pintles 519, 519' are, respectively, represented by dots V and V'.

A horizontal cylindrical pin 520 is mounted in a cylindrical hole 521, Fig. 4, of the same diameter, carefully bored and reamed 20 perpendicularly through bed 510 in any preferred position. The stationary axis of this hole is represented by a dot D. The pin 520 is thus mounted in order that it may easily be either inserted, or wholly withdrawn 25 after insertion, by simply sliding it as a bolt lengthwise along in its bearing.

On pin 520 or axis D is pivoted the 108 degree focusing sector comprising arms 516, 516' slotted radially at 517, 517', respectively, and rigidly connected by the stiffening arc 518. Cam slot 517 engages pintle 519 or axis V, while cam slot 517' engages pintle 519' or axis V'.

The upper end of groove 515, in bracket 35 514, and the upper end of slot 515', in bracket 514', are enlarged at the same level as axis D to form reamed bores 522 and 522', Fig. 1, of the same diameter as pin 520 for temporarily admitting such pin during the 40 process of adjustment, as fully explained later on in connection with Figs. 2 and 3. The axes of these two bores are represented by dots A and A', respectively.

When pin 520 is inserted in its bearing 45 521, Fig. 4, the axis of the pin coincides with the axis D of the bearing and it is held in fixed relation to the principal focal planes F and F' of the lens at distances x and x' from such planes. To illustrate this relation as clearly as possible the said horizontal distances x and x' are represented in the drawing as being imaginary horizontal bars x and x', respectively, connecting the principal focal planes F and F' of the lens 509 with the vertical plane through axis D. The 55 distances x and x' selected for illustration are x equal 17 centimeters and x' equal 37 centimeters; and their algebraic sum x plus x' or 54 centimeters is evidently equal to the 60 interfocal distance FF'. In cases where D is situated to the left of plane F, x is negative; and in cases where D is situated to the right of plane F', it is x' that is negative; so that the same rule, x plus x' equals FF', 65 is general for any desirable position of D.

The distance of axis A from the object plane P may be considered as determined by an imaginary horizontal bar m connecting the object plane P with the vertical plane through A; such distance being adjustable in length by the above described displacement of block 506 on carriage 512 to permit of satisfying the following equation:

$$m=x \quad (3) \quad 75$$

The distance of axis A' from the image plane P' may similarly be considered as determined by an imaginary horizontal bar m' connecting the image plane P' with the vertical plane through A'; such distance m' 80 being adjustable in length by the above described displacement of block 506' on its carriage 512' to permit of satisfying the following equation:

$$m'=x' \quad (4) \quad 85$$

In accordance with the rule followed in Figs. 12 to 15 of my Case T, bars x and x', being non-adjustable, are shown black to distinguish them from bars m and m', which are left white to indicate that they are adjustable.

As proved in my Case T in connection with Fig. 12 thereof, the mere act of making m equal to x is sufficient to insure that the 95 distance AD shall be and shall always remain equal to the variable left Newtonian space PF of the lens; similarly, the mere act of making m' equal to x' insures that the variable distance DA' shall be and shall 100 always remain equal to the variable right hand Newtonian space F'P' of the lens; that is to say, when equations 3 and 4 are satisfied we always have for all, either in or out of focus, positions of the end frames 105

$$AD=PF \quad (5)$$

and

$$DA'=F'P' \quad (6) \quad 110$$

whence

$$AD \cdot DA' = PF \cdot F'P' \quad 110$$

To secure correct focus, however, we must further satisfy Newton's formula, or equation 1 above, and we must, therefore, make

$$AD \cdot DA' = f^2 \quad (7) \quad 115$$

In equation 1 the spaces PF and F'P' are the Newtonian or constant product space elements of the lens; while in equation 7 the spaces AD and DA' are the corresponding 120 Newtonian or constant product space elements of the mechanism.

Fig. 4, which is a diagram of parts as seen in Fig. 1, shows the co-varying basic and always similar triangles VAD and 125 DA'V' with the angles marked as in Fig. 5 of my said Case Y (incorrectly referred to in my said Case Ae as Fig. 4).

The sector angle delta (Δ) may have any desired value, but it must be equal to the 130

bracket angles alpha (α) and alpha prime (α'); and we must, therefore, have

$$\alpha = \Delta = \alpha' \quad (8)$$

- 5 Angles omega (ω) and omega prime (ω') vary with every angular displacement of the focusing sector 518, but they vary so as to remain equal to each other; the same is also true of angles phi (φ) and phi prime (φ').
 10 In the triangles DVA and DA'V' the two distances AV and A'V', once adjusted for a given lens, remain invariable, but the four remaining distances DA, DV, DA', DV', shown dotted in Fig. 4, vary with every angular displacement of the focusing sector 518, and the variations are such that the triangles DVA and DA'V' remain similar while changing in shape, as proved in my said Case Y so that we always have

20

$$\frac{AV}{AD} = \frac{DA'}{A'V'}$$

whence

$$AV \cdot A'V' = AD \cdot DA' \quad (9)$$

25

and this, in view of equation 7, yields

$$AV \cdot A'V' = f^2 \quad (10)$$

30 The distances AV and A'V', which remain invariable after adjustment, may, therefore, be set and adjusted to any values AV and A'V' such that the product of AV and A'V' shall be equal to f^2 .

35 *Adjustment and regulation of the Fig. 1 camera.*

40 The lens 509, which may be any lens whose dimensions are within the extremes imposed by the unavoidable structural limits of adjustment, is first rigidly mounted in any preferred position on the lens frame L⁵, and then the focusing mechanism is adjusted and regulated, to coöperate therewith, by means of 3 separate adjustments as follows:

45 *Adjustment No. 1, determining m.*—The imaginary bar m , which is variable in length by adjusting frame O⁵ longitudinally along on carriage 512, must, according to equation 3, be made equal to x . This is done by focusing on right infinity in the special manner indicated in Fig. 2. The bolt 520 or D, Fig. 2, was first withdrawn sufficiently to permit of sliding carriage 512 up into the position seen in Fig. 2, where terminal A of the carriage falls in with terminal D of the lens and the bolt 520 or D was then pushed into bore 522 of bracket 514 to positively hold and lock the carriage 512 to bed 510 in the position illustrated.

55 This position of carriage 512, the position seen in Fig. 2, may be called its "zero position" because it is the position in which the left Newtonian space AD of the mechanism is at "zero value."

60 While carriage 512 is thus held in its

"zero position," the corresponding left Newtonian space PF of the lens is also reduced to zero value, and this is done by loosening screw 507, setting plane P in focus on right infinity, to make P coincide with F, 70 and then retightening screw 507.

This focusing on right infinity is done on screen 501 directly through the image frame I⁵, from which the screen 501' has temporarily been removed for the purpose, so 75 that the image frame I⁵ is, during such focusing operation, virtually absent as it should be, for its logical position during such operation is at right infinity.

Bar m is now and must henceforth remain equal to bar x , or in the case illustrated equal to 17 centimeters, so that bolt 520 or D may again be sufficiently withdrawn to free the now fully adjusted carriage 512, which is slid back, to the left, 85 to prepare for adjustment number two.

Adjustment No. 2, determining m'.—The imaginary bar m' , which is variable in length by adjusting frame I⁵ longitudinally along on carriage 512', must, according to 90 equation 4, be made equal to x' . This is done by focusing on left infinity in the special manner indicated in Fig. 3. The bolt 520 or D, Fig. 3, after completion of adjustment No. 1, was sufficiently withdrawn to free carriage 512 and it was, therefore, sufficiently withdrawn to permit of sliding carriage 512' up into the position seen in Fig. 3, where terminal A' of carriage 512' falls in with terminal D of 100 the lens. The bolt 520 or D was then pushed into bore 522' of bracket 514' to positively hold and lock carriage 512' to bed 510 in the position illustrated. This position of carriage 512', the position seen 105 in Fig. 3, may be called its "zero position" because it is the position in which the right hand Newtonian space DA' of the mechanism is at "zero value."

While carriage 512' is thus held in its 110 "zero position" the corresponding right hand Newtonian space F'P' of the lens is also reduced to zero value, and this is done by loosening screw 507', setting plane P' in focus on left infinity, to make P' coincide with F', and then retightening screw 507'.

This focusing on left infinity is done on screen 501', directly through the object frame O⁵, from which the screen 501 has 120 temporarily been removed for the purpose, so that the object frame O⁵ is, during such focusing operation, virtually absent, as it should be, for its logical position during such operation is at left infinity.

Bar m' is now, and must henceforth remain, equal to bar x' , or in the case illustrated equal to 37 centimeters, so that bolt 520 or D may again be sufficiently withdrawn to free the now fully adjusted car- 130

riage 512', which is slid back, to the right, to prepare for adjustment number three.

My case A explains that adjustment No. 2 may, and in some forms must, precede adjustment No. 1, hence it will be better hereinafter to distinguish these first two adjustments as "the m equal x adjustment" and "the m' equal x' adjustment."

Adjustment No. 3, determining AV and $A'V'$.—Space AV and space $A'V'$ may, as stated above, have any values such that their product $AV \cdot A'V'$ shall, in accordance with equation 10, equal f^2 or the square of the focal length FN of the particular lens 15 509 that is used. Either one of the two factors, AV or $A'V'$, considered as the first may, therefore, have its length fixed arbitrarily at any desired value, but the length of the second factor must, in order to satisfy 20 equation 10, be determined by adjustment, preferably as follows:

After the object frame O^s and the image frames I^s have both been positioned on their respective carriages 512, 512' by focusing on infinity in the order described above, or in reverse order, they are set and temporarily clamped in focus on each other, say with their carriages in the relative position shown in Fig. 1, where the copying 25 factor n is made exactly equal to 1.5, for clearness only, as no attention is paid to its exact value. One of the two pintles, V or V' , is then fixed at any preferred point of its respective groove 515 or 515'. Let 30 519 or V be such pinte and let the selected distance AV be 32 centimeters, as shown in Fig. 1. The sector 516, 516' is now mounted on its pivot 520 or D and in proper engagement with such previously fixed pinte 519 or V , as seen in Fig. 1, and the other end frame pinte, here 519' or V' , will then have to be inserted where its inclined groove 515' is met by the radial slot 517', or at 35 18 centimeters from A' .

40 The clamps used to hold frames O^s and I^s temporarily in focused relation on each other are now removed, and the device is ready for use.

After completion of the adjustments 1, 2, 45 and 3 just described, planes P and P' are obliged to move together and at such rates as to remain sharply focused on each other. If, therefore, a negative be mounted in the object frame O^s and the frames be moved, the 50 image of such negative will appear on screen 501' changing in size, but remaining sharply focused and distinct, except in so far as distinctness is unavoidably affected by expansion or contraction of the image.

55 60 Pintles V , V' when set at shown in Fig. 1 move in offset horizontal planes with V in the lower plane; but if the carriages 512, 512' be temporarily clamped in any finite focal relation, that of Fig. 1, for instance, 65 and the pintles V , V' both be loosened, any

other desired coöperative pair of values may be given to the vectors AV and $A'V'$ to make V move in the same horizontal plane as V' , or even in a higher plane, by simply rotating the sector 518 so as to shift the pintles V and V' along in their respective grooves 515 and 515' from the positions shown in Fig. 1 into any other desired pair of conjugate positions in which they can be reclamped to their respective brackets to 70 operate as before. This is because in every possible angular position of the sector 518 the radial sector slots 517, 517' respectively meet grooves 515, 515' so as to determine distances AV and $A'V'$ whose product 80 $AV \cdot A'V'$, as in equation 9, is equal to $AD \cdot DA'$, and, as long as the latter product $AD \cdot DA'$ is kept invariable by the temporary clamps, the former product $AV \cdot A'V'$ must remain constant.

85

Structural conditions in Fig. 1.

The strictly necessary structural conditions, which are all satisfied in a perfectly adjusted device such as that of Fig. 1, are 90 summed up in equations 8, 3, 4, and 10, here grouped and renumbered for convenience as equations 11, 12, 13, and 14.

$$\alpha = \Delta = \alpha' \quad (11) \quad 95$$

$$m = x \quad (12)$$

$$m' = x' \quad (13)$$

$$AV \cdot A'V' = f^2 \quad (14)$$

These four equations are substantially identical with equations 1, 2, 3, and 4 of my said 100 Case Y.

In present Fig. 1, equation 11, which relates exclusively to the angles best seen in Fig. 4, is satisfied by constructing the brackets 514, 514' so that their respective grooves 105 515, 515' shall have the proper inclinations determined by the sector angle delta (Δ). Equations 12, 13, and 14 are severally satisfied by the three focusing adjustments described above.

The numerical values, which may directly be verified in the drawings, are collected in the annexed table, Table A, which contains a complete list of all fundamental or rigid dimensions which remain invariable after 115 completion of the three adjustments.

Table A of fundamental dimensions in the camera of Figs. 1 to 4.

$\alpha = \Delta = \alpha' = 1.20$ Q
$f = FN = N'F' = 24$ cm $FF' = 2^2 + NN' = 54$ cm $f^2 = 24 \text{ cm} \times 24 \text{ cm} = 576 \text{ cm}^2$
$m = x = 17$ cm $m' = x' = 37$ cm $(m + m') = (x + x') = 54$ cm = FF'
$AV = 32$ cm $A'V' = 18$ cm $AV \times A'V' = 32 \text{ cm} \times 18 \text{ cm} = 576 \text{ cm}^2 = f^2$

120

125

130

The values of the co-variables of Fig. 1, which vary with every change made in the copying factor, have also been adhered to in many of the other Case Ae figures and they 5 are, therefore, collected in the annexed Table B:

Table B of co-variables in Fig. 1 (also in Fig. 4 and in the Case Ae Figs. 5, 6, 9, 10 11, 14, 20, and 21.)

Left hand Newtonian space.....	PF = AD = 16 cm
Right hand Newtonian space...	F'P' = DA' = 36 cm
Copying factor $n = \frac{P'W}{PW} = \frac{P'N'}{NP} = \frac{P'F'}{PF} = \frac{f}{PF} = \frac{3}{2} = 1.5$	

15 It is evident that the camera of Fig. 1, for instance, may be used: first, to produce a copy PW of an original P'W' at the right; secondly, to produce a copy P'W' of an original PW at the left. In the first case the copying factor is the ratio of PW to P'W', and in the second it is the inverse ratio of P'W' to PW. This last ratio, P'W'/PW, in which the light proceeds from left to right, is the 20 one given in the above Table B, and it is the one that is adhered to throughout my Case Ae specification, simply to avoid the confusion that would result from the use of two reciprocal values of the copying factor for 25 the same given position of the end planes P and P'; and not with any idea of fixing the direction in which the copy is to be made. In accordance with the same convention, the left end frame is invariably referred to as 30 the "object frame," even in combinations where it would normally be used as light receiving or image frame.

The two radial cams, illustrated in connection with arms 516, 516', turn in a constant 35 angular relation, maintained, for example, by stiffening arc 518. Broadly speaking, this angular relation is equal to the sum of two smaller angles, the first of which is the basic angle delta (Δ) of the focuser, as herein 40 explained, while the second of said angles is equal to the angle between the paths of movement described by pintles V and V' or, differently expressed, the angle between the paths of movement of the object 45 plane support and image plane support. Of course, in the simple case, shown in Fig. 1, the second of these angles is equal to zero, the pintles moving in parallel paths.

NOTE 1.—Where the basic angle delta (Δ) 50 is made larger than in the present Fig. 1, as large say, as in my Case Ae Figs. 5 and 6, the focuser is locked, by friction, in nearly every position of the mechanism; but, it may be rendered fully operative either by the slight 55 alteration which converts it in a "single sight" focuser of the type shown in my said Case Ae Fig. 10; or by the less simple, but still conveniently made, alteration which

converts it into a "single sight" focuser of the type seen in my said Case Ae Fig. 11, 65 and in my said Case Be Fig. 1.

NOTE 2.—One of the focuser terminals, either V or V', may be permanently fixed on its respective carriage, as shown in my Case Ae Fig. 7, for terminal V'. 70

NOTE 3.—One of the terminals A or A' may be made imaginary, as shown in my Case Ae Fig. 8, for terminal A'.

NOTE 4.—Terminals A and A' may both be made imaginary, as shown in my Case Ae 75 Fig. 10; also in Fig. 1 of my said Case Be.

NOTE 5.—The general 3-point method of adjustment, with all three adjusting n -values finite, as disclosed in my said Case Au, Fig. 7, page 7, line 14, to page 8, line 48, and there 80 stated (page 8, lines 9 to 20) to be applicable to my said Cases K, O, T, U, Y, Ab, Ae, At, and also X, is equally applicable to all forms of the present Case Bf.

NOTE 6.—In view of Fig. 2, it is plain that 85 terminal A is the zero position of pivot D with relation to the object frame O⁵; and similarly, in view of Fig. 3, it is plain that terminal A' is the zero position of pivot D with relation to the image frame I⁶. 90

What I claim and desire to secure by Letters Patent is:

1. A copying or enlarging camera having a wholly mechanical focuser which is of the radial cam type, and whose basic angle, 95 herein designated by delta (Δ), is larger than a right angle.

2. The combination with a copying or enlarging camera comprising (1) an object plane support, (2) a lens support, and (3) an 100 image receiving plane support; also guideways to permit of setting said 3 supports in any desired conjugate relation to produce, from a given object held in the said object plane support, a sharply focused image of 105 any desired size; of focusing mechanism connecting said three supports so as to oblige two of them to move with relation to the third, without change in the sharpness of the image excepting such as may inevitably 110 be associated with a change of size; said focusing mechanism being of the type comprising two radial cams connected to rotate in constant angular relation, this angular 115 relation being the sum of two smaller angles, one of which is the basic angle of the focusing mechanism and the other of which is equal to the angle between the paths of movement of said object plane support and said image plane support.

In testimony whereof, I have signed my name to this specification in the presence of Mrs. Mary E. Cowell. 120

JOSEPH BECKER.

Witness:

MARY E. COWELL.
